ROLLER SCREEN STRUCTURE

Filed Feb. 19, 1927

UNITED STATES PATENT OFFICE

HARRY DIXSON, OF PELLA, IOWA, ASSIGNOR TO ROLSCREEN COMPANY, OF PELLA, IOWA

ROLLER-SCREEN STRUCTURE

Application filed February 19, 1927. Serial No. 169,554.

My invention has to do in a general way with the provision of certain improvements for screens for windows and the like and particularly with screens of the type which may be roller up when not in use and unrolled to cover the window opening when desired.

It is my particular purpose to provide in such a screen structure, a case for the rolled-up screen and guide tracks for receiving the side edges of the screen when the screen is unrolled and withdrawn from the case, the guide tracks being adapted to permit the withdrawal of the screen edges without injury to the screen or tracks or case.

Particularly, it is my purpose to provide in this connection, track and case structures which will permit the screen to move back into its normal place after having been withdrawn from the guide tracks without the necessity for disassembling the parts.

With these and other objects in view, my invention consists in the construction, arrangement and combination of the various parts of my roller screen structure, whereby the objects contemplated are attained, as hereinafter more fully set forth, pointed out in my claims, and illustrated in the accompanying drawings, in which:

Figure 1 is a perspective view of a portion of a roller screen structure embodying my invention, showing one end of the casing, a portion of the screen and a portion of one of the guide tracks.

Figure 2 is a front elevation of the mechanism shown in Figure 1.

Figure 3 is a front elevation with parts shown in section and parts broken away illustrating the action of the screen under certain circumstances.

Figure 4 is a detail, sectional view taken on the line 4-4 of Figure 3.

Figure 5 is a side elevation of one of the tracks of a slightly modified form of construction; and

Figure 6 is a detail, sectional view taken on the line 6-6 of Figure 1.

In the accompanying drawings, I have used the reference numeral 10 to indicate generally the screen case which is adapted to support and contain the shaft 12 upon which is

mounted the screen roller 14 for the screen 16. The manner of mounting the roller on the shaft is not material to the present invention, but it will be understood that some standard construction is employed, whereby the roller is yieldingly mounted to rotate for rolling the screen upon the roller when the screen is withdrawn from the case.

The case 10 has a portion of its bottom near its front end cut away to leave a slot 18 for the passage of the screen 16.

The front wall of the case is preferably cut away at its lower edge as indicated at 20 for the purpose which will be hereinafter more fully explained.

When installed for windows, the case 10 is mounted preferably at the top of the window and set into the window frame.

At the sides of the window frame below the case are opposite guides A. Each guide preferably is formed with the flat flange member 22 and the tubular portion 24 for receiving the edge of the screen.

The tubular portion 24 is resilient and has the longitudinal slot 26 between the narrow flanges 28.

The flange 22 may be double and is extended above the tubular portion 24 of each guide track and projected into the case 10 as indicated at 30 in Figure 4.

The screen 16 has a stiff binder 32 at its lower edge.

The side edges of the screen are provided with thickened lugs or portions 34. The parts are so constructed and arranged that when the screen is pulled out of the case 10, the side edges of the screen project through the slots 26 into the tubular portions 24 of the guide tracks.

One difficulty, which frequently occurs with screens of this kind, arises when a sharp blow is struck on the screen. That blow tends either to pull the edges of the screen from the guide tracks or to injure the tracks or to tear the screen.

To avoid injury to the tracks, screen or case, the tracks are made of resilient material, so that when the screen is withdrawn from the case and is subjected to any blow of the kind under consideration, the side

edges having the thickened lugs or the like 34 may be pulled out of the guides through the slots 26.

There then arises the problem of how to get the edges back into the tracks or to cause the screen to roll into the case and upon the roller without buckling.

For accomplishing this returning of the screen to normal position, I have provided in the tracks the notches 36, such for instance as are indicated in Figures 1 and 2.

In those figures, I have shown a portion of the screen below the notches pushed out of the guide tracks.

When this is done, and the screen is pushed upwardly for rolling it into the case, the side edges of the screen will slide over the lower edges of the notches and then enter the guide tracks, as illustrated in Figures 1 and 2.

The notches 36 are preferably cut in both sides or halves of the guide tracks.

In that case, if the side edges of the screen are pushed out of the tracks, either inwardly or outwardly, the screen will readily travel back into place, as it is rolled up.

I find, however, that the result can be accomplished by cutting a notch 36a in one member only of the guide track, as illustrated in Figure 5.

Where that structure is used, if the screen is punched out in the direction indicated by the arrow 38 in Figure 5, then when the screen is moved toward the case, its side edges will move back into the guide tracks in the way already explained.

If, on the other hand, the screen has been pushed out in the direction indicated by the arrow 40 in Figure 5, it will then be necessary to push that part of the screen which has been withdrawn from the tracks to the left, and thereupon the movement of the screen toward the case will cause its side edges to move back into the guide tracks.

Sometimes, however, the screen is pulled out of the tracks above the notches 36 or 36a, as the case may be.

For making it certain that the screen will not buckle upon being rolled up in such a case, I have cut away the lower front portion of the front wall of the case 10 as indicated at 20 (see Figure 4).

When this is done and assuming that the screen does not return to position through the slots 36 or 36a, it will be seen that the edges of the screen, which have been pulled out of the guide tracks will travel upwardly as the screen is rolled up over the upper edge of the tubular portion 24 of the screen and then slide through the opening 20 to normal position.

It is my intention to show in the drawings filed herewith certain forms in which my invention may be embodied, but it is not my purpose to limit myself by the drawings to

anything less than the real invention disclosed.

I claim as my invention:

1. In a structure of the class described, a guide track having an attaching flange, a tubular portion provided with a slot opening away from the flange, said guide track being provided at a point spaced from its ends with a notch extending from the slot substantially into the tubular portion and having its upper side edge arranged at an angle to horizontal. 75 75

2. In a structure of the class described, a guide track having an attaching flange, a tubular portion provided with a slot opening away from the flange, said guide track being provided at a point spaced from its ends with a notch extending from the slot substantially into the tubular portion, the upper edge of the notch being inclined upwardly from the tubular portion towards the slot, whereby the side edge of a flexible screen having a tendency to normally straighten itself transversely and adapted to normally travel in said tubular portion may be rethreaded into said portion in the event of its withdrawal therefrom by being accidentally bowed transversely. 80 85 90 95
